UNITED STATES PATENT OFFICE

127,558

DESIGN FOR A DOOR LATCH

Richard T. Anderson, Stacy, Minn.

Application August 1, 1940, Serial No. 94,116

Term of patent 14 years

To all whom it may concern:

Be it known that I, Richard T. Anderson, a citizen of the United States, residing at Stacy, county of Chisago, and State of Minnesota, have invented a new, original, and ornamental Design for a Door Latch, of which the following is a specification, reference being had to the accompanying drawing, forming part thereof.

I claim:

The ornamental design for a door latch, as shown.

RICHARD T. ANDERSON.
